UNITED STATES PATENT OFFICE.

DENIS DOODY, OF MONTREAL, QUEBEC, CANADA.

SHIPPING BOX.

Application filed November 5, 1921. Serial No. 513,182.

To all whom it may concern:

Be it known that I, DENIS DOODY, a subject of the King of Great Britain, residing at Montreal, in the Province of Quebec, Canada, have invented certain new and useful Improvements in Shipping Boxes; and I do hereby declare that the following is a full, clear, and exact description of the invention, such as will enable others skilled in the art to which it appertains to make and use the same.

The present invention relates to new and useful improvements in collapsible or rigid shipping cases to be made from wood, or any pliable material.

The primary object of the invention is the provision of a collapsible box or shipping case formed from suitable material connected by end members which retain the same in extended position.

Another object of the invention is the provision of a shipping case or box having metallic end frames for securing the end members in position and likewise holding the top, bottom and side members in proper relative position, the said box being capable of collapsing when the said end frames are removed.

Still another object of the invention is the provision of a box having novel means for locking the closure in position, so that the same can be sealed to prevent unauthorized opening or to prevent the same from being tampered with in any manner whatsoever.

A still further object of the invention is the provision of a collapsible box such as above referred to which will be comparatively simple and inexpensive to manufacture, reliable and efficient in use, and readily operated.

With the above and other objects in view, the present invention resides in the novel features of construction, formations, combinations and arrangements of parts to be hereinafter more fully described, claimed, and illustrated in the accompanying drawings, forming a part of the present application, and in which:

Figure 1 is a perspective view of the box, with the cover in closed position;

Figure 2 is a similar view of one end thereof showing the closure unlocked and ready for opening;

Figure 3 is a longitudinal sectional view taken through one end of the box on a vertical plane; and,

Figure 4 is a similar view taken on a horizontal plane.

Figure 5 is a plan view of the blanks from which the box is formed;

Figure 6 is a plan view of the blank from which one of the end frames is formed; and,

Figure 7 is a perspective view showing the end frame partly bent to the position for receiving the ends of the body portion.

Referring now to the accompanying drawings by corresponding characters of reference throughout the several views, the numeral 10 designates in general my improved box which consists of the opposite side members 11, a bottom 12, top 13, and end members 14. The top, opposite sides, and bottom of the box are all formed from a single blank of material, shown in Figure 5, while the end members 14 are formed from smaller blanks which are likewise shown in Figure 5.

The end frames 15 which secure the top, bottom, side and end members together, consist of single strips of material formed in sections 16 so arranged that they can be bent into rectangular form as shown in Figure 1. The members may also be bent longitudinally to provide gripping flanges 17 for engaging the foldable end flanges 18 formed on the top, bottom and side members, while the opposite sides thereof are formed with flanges 19 which when bent form grooves 20 for the insertion of the members 14 therein.

The adjacent ends of the sections are cut away, as shown at 21 so that the same can be properly bent without interference.

A locking tongue 22 is provided upon the upper section 16 and is designed to engage a notch 23 formed in the adjacent end of the section 16 which engages the opposite side of the box. The tongue 22 is also formed with a notch 24 for interlocking engagement with the notch 23, while the material adjacent these notches is provided with aligning openings 25 designated to receive a suitable sealing means, whereby the box can be sealed and prevented against unauthorized opening.

In use the end frames 15 are bent along the dotted lines, as shown in Figure 6, to the position shown in Figure 7, and then into the rectangular shape, as shown in Figure 1 with the top, bottom and side members firmly gripped therebetween, and the end members 14 fitted in the grooves 20. The top is provided with a locking flange 26

which projects over one of the side members for holding the contents of the container against displacement.

If it is found desirable to construct the box or shipping case from wood or other similar material, the top, bottom and side members are separable and so grooved as to receive the metallic end members bent in opposite directions.

It will be seen from the foregoing description taken in connection with the accompanying drawings, that a box is provided which can be used for shipping purposes and the like and which will fulfill all of the necessary and desired requirements, and it will also be seen that by removing the end members 14 the box can be collapsed or folded out flat, so that a number of boxes can be shipped at one time, and also to require but very little space for storage.

It should also be manifest that a box is provided which will fulfil all of the necessary requirements of such a device, and it should be understood in this connection that the body may be constructed from any suitable material and that the top, bottom and side members may be formed integral or formed in separate sections as might be desired and hinged together, and it shall be additionally noted that various minor changes in the specific details of construction can be resorted to within the scope of the appended claims, without departing from the spirit or sacrificing any of the advantages of the invention.

Having thus fully described the invention,

what I claim as new and desire to protect by Letters Patent is:—

1. The herein described box, comprising a body portion, consisting of a top, bottom and side members, end members engaging the free edges thereof, a frame for securing the box rigidly against displacement and holding the said end members in position, including flanges adapted for attachment to the top and bottom of the box and flanges forming grooves for receiving the end members, one end of each frame having a notch therein, and a flange on the end of each frame having a notch therein for engaging the notch in the frame, as and for the purposes set forth.

2. The herein described box, comprising a body portion, consisting of a top, bottom and side members, end members engaging the free edges thereof, a frame for securing the box rigidly against displacement and holding the said end members in position, including flanges adapted for attachment to the top and bottom of the box and flanges forming grooves for receiving the end members, one end of each frame having a notch therein, a flange on the end of each frame having a notch therein for engaging the notch in the frame, the said frames and their flanges having openings therein, registering when the box is in operative position, as and for the purposes set forth.

In witness whereof I have hereunto set my hand.

DENIS DOODY.
